UNITED STATES PATENT OFFICE.

JOHN KIRKALDY, OF POPLAR, COUNTY OF MIDDLESEX, ENGLAND.

CONDENSER AND HEATER.

SPECIFICATION forming part of Letters Patent No. 311,839, dated February 3, 1885.

Application filed May 19, 1884. (No model.) Patented in England May 3, 1884, No. 7,200; in France May 8, 1884, No. 161,987, and in Belgium May 9, 1884, No. 65,118.

To all whom it may concern:

Be it known that I, JOHN KIRKALDY, a subject of the Queen of Great Britain, residing at 40 West India Dock Road, Poplar, in the county of Middlesex, England, engineer, have invented certain new and useful Improvements in Surface Condensers and Heaters, (for which I have secured Letters Patent in Great Britain, No. 7,200, dated May 3, 1884; in France, No. 161,987, dated May 8, 1884, and in Belgium, No. 65,118, dated May 9, 1884,) of which the following is a specification.

In the specification of a former patent granted to me in England, No. 1,816, in the year 1883, I described a surface-condenser in which helical worms were placed parallel with one another within a metal casing, steam was admitted to one end of each coil, and the other end of each coil opened into a chamber from which the condensed water could be pumped or drawn off. Cold water was admitted to the bottom of the outer metal casing and passed off from the top.

The object of my present invention is to increase the efficiency and working capacity of condensers of this kind, or of similarly-formed heaters.

According to my present invention I make each tube, as before, in the form of a helical coil. I place the several helical coils side by side and close together, so that the coils of one tube may pass into the spaces between the coils of the adjacent tubes. Preferably, I range them in this way in a circle and surround them with a circular casing. I also make them of alternately right and left handed worms, so that they may the better fit the one into the other. The condensers may either be made with a single circle of such adjacent helical worms, or they may be made with two or more circles one within the other. At the upper end of each helical coil the tube of which it is formed is bent upward and passed through a tube-plate, two nuts are screwed onto the end of each tube, one to bear against the inside of the tube-plate, the other to bear against its outside; or, in place of the nut on the inside, the tube might have brazed onto its end a short length of tube screwed externally, and formed with a collar at its inner end. In a similar manner the lower end of each tube is

passed through and secured to a tube-plate. The top tube-plate passes across the top of the cylindrical casing which surrounds the assemblage of helical coils. The bottom tube-plate passes across the bottom of this casing. Above the top tube-plate is a chamber to which the steam to be condensed is conducted by a suitable pipe; and below the bottom tube-plate is a chamber into which water produced by the condensation of steam flows from the worms, and, if the condenser is being used as the condenser of a steam-engine, is removed from this chamber by pumping. Water is introduced into the lower part of the casing through a pipe which rises up through the center of the bottom tube-plate, and is allowed to pass off from the upper part of the casing through an overflow-pipe. In some cases in place of water being used for cooling the tubes, they might be cooled by exposure to the atmosphere or to a forced current of cold air. As a heater the construction is the same, but the water or other fluid to be heated would be admitted to the tubes and steam to the casing.

In the drawings hereunto annexed I have shown two examples of surface-condensers constructed as above described. In the condenser shown at Figures 1, 2, 3, and 4 there is a single circle of spiral worms, with a single spiral worm in the center. In the condenser shown at Figs. 5 and 6 there are three concentric circles of spiral worms.

Fig. 1 is a vertical elevation, with one-half in section, of the outer casing of the condenser. Fig. 2 is a vertical elevation of the condenser with the outer casing in section. Fig. 3 is a plan view, and Fig. 4 a plan view with the top cover and tube-plate removed.

In these figures, A is the outer casing, with a steam-chamber, B, at the top, and chamber C, for condensed water, at the bottom.

D are the spiral worms passing at their upper ends through the top tube-plate, E, and at their lower ends through the bottom tube-plate, F. It will be seen that the coils of one worm pass into the spaces between the coils of the worms which are on either side of it, and also that the spiral worms are alternately right and left handed to permit of their thus being made to interlock with one another.

G is the inlet-pipe for admitting water to

the lower part of the casing A. It is carried up nearly to the top of the casing A, so that the water within it may to some extent cool the water in the upper part of the casing.

5 G' are holes formed through the pipe G, through which water is forced out into the lower part of the interior of the casing. H is an outlet-passage by which water can pass off from the top of the casing. The chamber C 10 is also formed with an outlet-passage by which water produced by the condensation of steam in the worms D can be pumped off from it. This outlet is not shown in the drawings.

The construction of the condenser shown at 15 Figs. 5 and 6 is similar to the one just described, except that, as before stated, it is formed with three concentric rings of interlocking spiral worms, one ring within the other. The same parts are lettered with the 20 same letters of reference as in Figs. 1, 2, 3, and 4, so that it is unnecessary to give any further description of it.

In place of the condensers being placed vertically, they might be placed horizontally. I however prefer to place them vertically, 25 so that water resulting from the condensation of steam may flow off from the spiral worms by gravitation.

Having now particularly described and ascertained the nature of my said invention and 30 in what manner the same is to be performed, I declare that what I claim is—

The combination of the parallel alternately right and left handed spiral worms arranged with the coils of each worm passing into spaces 35 between the coils of the adjacent worms and their casing, substantially as and for the purpose set forth.

JOHN KIRKALDY.
